(57) **CLAIM**

The ornamental design for a dual dispenser package with dual actuators, as shown and described.

DESCRIPTION

FIG. 1 is an exploded view including overcap of the first embodiment of a dual dispenser package with dual actuators;

FIG. 2 is a front view with overcap attached thereof;

FIG. 3 is a right-view, which is a mirror image of the left-side view thereof;

FIG. 4 is a rear view attached thereof;

FIG. 5 is a top view attached thereof;

FIG. 6 is a bottom view attached thereof;

FIG. 7 is an isometric view;

FIG. 8 is an isometric view with overcap removed, of the second embodiment of a dual dispenser package with dual actuators;

FIG. 9 is a front view thereof;

FIG. 10 is a right-view, which is a mirror image of the left-side view thereof;

FIG. 11 is a rear view thereof;

FIG. 12 is a top view thereof; and,

FIG. 13 is a bottom view.
